UNITED STATES PATENT OFFICE.

WILLIAM S. DEANS, OF PITTSBURGH, PENNSYLVANIA, ASSIGNOR, BY MESNE ASSIGNMENTS, TO ECLIPSE MACHINE COMPANY, OF ELMIRA HEIGHTS, NEW YORK, A CORPORATION OF NEW YORK.

ENGINE STARTER.

Application filed October 24, 1923. Serial No. 670,531.

My invention relates to engine starters, and it has particular relation to starters for internal-combustion engines of automobiles or other motor vehicles.

5 My invention has for one of its objects to provide an engine starter that is automatically operatively connected to an internal-combustion engine upon the operation of the starting motor.

10 A second object of my invention is to provide an engine starter of the character described above wherein a member that is movable axially of a pinion operates automatically to shift the pinion in the plane of its rotation into and out of engagement with a co-acting member.

15 An engine starter constructed in accordance with my invention comprises a member that is operatively connected to the shaft of the starting motor in such manner as to be moved longitudinally upon the rotation of the shaft. The longitudinally movable member coacts with the driving pinion to actuate the latter radially or in the plane of its rotation up the outward movement of the longitudinally movable member.

20 In the accompanying drawing,

Figure 1 is a view, partially in elevation and partially in section, of a portion of an engine flywheel and an engine starter constructed in accordance with my invention;

25 Fig. 2 is a view, similar to Fig. 1, illustrating the pinion in engagement with the flywheel gear;

30 Fig. 3 is a view in end elevation of the mechanism of Fig. 2.

Referring to the drawing, an engine flywheel 1, only a portion of which is shown, is provided with gear teeth 2. A starting motor 3, which may be, for example, an electric motor, is provided with an armature shaft 4 having a hollow bore, indicated at 5.

35 The hollow portion of the shaft 4 is occupied by a short shaft 6 that is connected to the armature shaft 4 by a pin 7 and helical slots 8. The shaft 6 is provided at an intermediate portion with a flange 9 having a radially-extending slot 10 therein. The outer portion of the shaft 6 is tapered at 11 to provide an end portion of substantially cone shape.

40 An end casting 13, which provides a bearing support for the shafts 4 and 6, is provided with radially-extending lugs 14 where-

5 by the motor and its associated parts may be secured to the flywheel housing (not shown). The casting 13 is provided, also, with a projecting portion 15 for supporting the bearing 16 of a stub shaft 17 that is integral with a pinion 18. The bearing 16 is retained in position by means of a supporting member 19 that is bolted or otherwise secured to the projection 15. The shaft 17 and the pinion 18 are retained in the bearing 16 by means of a collar 20 that is pinned to the outer end portion of the shaft 17.

55 The bearing 16 is mounted in an oblong slot 21 in the members 15 and 19 for vertical movement relatively to the latter members, and is maintained in horizontal alinement 60 during this movement by means of vertically-extending pins 22 and 23. A spring 24 normally holds the bearing 16 and the pinion 18 in their uppermost positions in which they are illustrated in Fig. 1.

65 The pinion, on its side adjacent to the motor, is provided with a flange 25 and with a relatively deep recess 26 that is tapered at its inner portion at substantially the same angle as the conical surface 11 of the shaft 6. The flange 25 carries a pin 27 that extends into the slot 10 in the flange 9 to operatively connect the pinion 18 to the shaft 6 and thereby to the shaft 4 of the motor.

70 Normally, the several parts are in their respective positions in which they are illustrated in Fig. 1. When the motor 3 is energized in any usual or suitable manner by means not shown, the shaft 4 rotates in a clockwise direction, as viewed from the left 75 in Fig. 1. By reason of the inertia of the shaft 6, the pinion 18 and associated parts, the shaft 4 rotates relatively to the shaft 6, and the latter is actuated outwardly by reason of the cam action of the inclined surfaces of the slots 8 that are engaged by the pin 7.

75 The longitudinal outward movement of the shaft 6 causes the conical surface 11 to exert a cam action upon the inclined surface of the recess 26 in the pinion 18, and the latter, together with the bearing 16 and pins 22 and 23, are moved downwardly against the force of the spring 24 until the shaft 17 is in axial alinement with the shaft 6. The parts are then in their respective positions in 80 which they are illustrated in Fig. 2, the pinion 18 being completely meshed with the flywheel gear 2. The motor thereupon drives

the pinion 18 through the shaft 4, shaft 6, flange 9, pin 27 and flange 25.

When the engine is started and operates under its own power, the pinion 18 becomes the driven member and is rotated at a speed that is higher than that of the shaft 4. Accordingly, the shaft 6 is rotated relatively to the shaft 4 and the inclined surfaces of the slots 8 exert a cam action to actuate the shaft 6 to the left, as viewed in Fig. 1. As the shaft 6 is withdrawn from the recess 26, the spring 24 actuates the pinion 18 and its associated structure upwardly out of engagement with the flywheel gear 2. When this operation is completed, the several parts again occupy their normal positions. The circuit of the motor may be opened by the operator at any desired time after the starting of the engine.

An engine starter constructed in accordance with my invention possesses the advantages that it is automatically connected to the engine upon the operation of the motor. Comparatively simple means are provided whereby longitudinal movement of one member effects movement of another member at right angles thereto to complete the operative connection of the motor to the engine. The device operates without shocks caused by impact of rapidly moving parts, such as are incident to the operation of engine starters embodying pinions that are axially movable into engagement with the engine flywheel.

I claim as my invention:

1. In an engine starter, the combination with an engine member and a pinion movable in the plane of said engine member into and out of engagement therewith, said pinion having a conical recess therein coaxial with and open at one face of such pinion, of means movable axially of said pinion and coacting with said recess for controlling the position of the pinion and for rotating the latter and including a longitudinally movable shaft terminating in a conical end which cooperates with said conical recess.

2. In an engine starter, the combination with an engine member and a pinion movable in the plane of rotation of said engine member into and out of engagement therewith, said pinion having a central substantially conical recess in one face thereof, of a motor having a shaft, means for automatically actuating said pinion into engagement with said engine member upon rotation of said motor shaft, said means including a member having an inclined end-surface entering said pinion recess and means maintaining constant driving connection between said motor shaft and said pinion at a place on said pinion radially beyond the confines of said recess.

3. In an engine starter, the combination with an engine member and a pinion movable in the plane of rotation of said engine member into and out of engagement therewith,

of means for biasing said pinion to its disengaged position, a motor and means for automatically actuating said pinion into engagement with said engine member upon the rotation of said motor, said means comprising a member movable longitudinally of the motor shaft and engaging said pinion, certain of the engaging surfaces of said members being of substantially conical form.

4. In an engine starter, the combination with an engine member and a pinion movable in the plane of rotation of said engine member into and out of engagement therewith, of means for biasing said pinion to its disengaged position, a motor and means for automatically actuating said pinion into engagement with said engine member upon the rotation of said motor, and thereupon rotating said pinion, said means comprising a member movable longitudinally of the motor shaft and being operatively connected thereto by a pin-and-slot connection, said member exerting a cam action on said pinion and being operatively connected thereto.

5. In an engine starter, an engine member and a pinion movable in the plane of its rotation into and out of engagement with said engine member, of a motor, and a member having a cam engagement with, and an operative connection to, said pinion, and a pin-and-slot connection to the shaft of said motor for longitudinal movement relatively thereto.

6. In an engine starter, the combination, with a pinion mounted for rotation and for movement transversely of its axis but fixed as to movement longitudinally, of means in constant driving relation rotarily with the pinion and including a shaft longitudinally movable and having a conical end, said pinion having a central conical recess with which said conical end of the shaft cooperates to move the pinion transversely of its axis.

7. In an engine starter, the combination, with a pinion mounted for rotation and for movement transversely of its axis but fixed as to movement longitudinally, of means in constant driving relation rotarily with the pinion and including a member movable longitudinally and cooperating with the pinion to move it transversely of its axis, a motor having a shaft provided with a pin and inclined slot connection with said member for so moving it longitudinally.

8. In an engine starter, the combination of a motor having an extending bracket, a shaft having at one end a driving member and mounted at the other end in the bracket for rotary movement and for movement transverse of its axis, and means operated by the motor for rotating the driving member and for camming it transversely of its axis.

9. In an engine starter, the combination of a motor having an extending bracket, a

shaft having at one end a driving member and mounted at the other end in the bracket for rotary movement and for movement transverse of its axis, and means operated by the motor for rotating the driving member and for moving it transversely of its axis, said motor having a driving shaft and said means including a shaft intermediate the other two shafts and operatively connected with said driving member and said driving shaft.

10. In an engine starter, the combination of a motor having an extending bracket, a shaft having at one end a driving member and mounted at the other end in the bracket for rotary movement and for movement transverse of its axis, and means operated by the motor for rotating the driving member and for moving it transversely of its axis, said motor having a driving shaft and said means including a shaft intermediate the other two shafts and operatively connected with the motor shaft for rotation therewith and for longitudinal movement thereof as a result of the rotation of the motor shaft, said driving member having at one end a central conical recess and said intermediate shaft having its adjacent end formed conical to operate with said recess.

25 a result of the rotation of the motor shaft, and cooperating with the driving member to rotate it and move it transversely of its axis.

11. In an engine starter, the combination of a motor having an extending bracket, a shaft having at one end a driving member 30 and mounted at the other end in the bracket for rotary movement and for movement transverse of its axis, and means operated by the motor for rotating the driving member and for moving it transversely of its axis, 35 said motor having a driving shaft and said means including a shaft intermediate the other two shafts and operatively connected with the motor shaft for rotation therewith and for longitudinal movement thereof as a 40 result of the rotation of the motor shaft, said driving member having at one end a central conical recess and said intermediate shaft having its adjacent end formed conical to operate with said recess.

45 In testimony whereof, I have hereunto subscribed my name this 9th day of October 1923.

WILLIAM S. DEANS.
